United States Patent

Des. 234,860
Patented Apr. 15, 1975

234,860

SET OF CHESS PIECES

Joseph S. Bush, 3751 Glenmeade Road,
Louisville, Ky. 40218

Filed Feb. 7, 1973, Ser. No. 330,326

Term of patent 14 years

Int. Cl. D21—01

U.S. Cl. D34—5 CH

The figure is a perspective view of the set of chess pieces showing my new design, the opposite sides of said pieces being substantially the same as that shown.

I claim:

The ornamental design for a set of chess pieces, substantially as shown and described.

References Cited

UNITED STATES PATENTS

3,511,504 1/1968 Mann et al.

FOREIGN PATENTS

21,239 1909 Germany ----- 273—137 R

OTHER REFERENCES

Industrial Design, August 1964, p. 67, upper left, cans.
Glass Packaging, December 1963, p. 43, bottle.
Packaging Packjngen Emballages, 1959, p. 94, illustration No. 180.

MELVIN B. FEIFER, Primary Examiner